OPEN-TOP REFRIGERATED DISPLAY CASE

Nicholas Achs, Detroit, Mich.

Application January 26, 1948, Serial No. 4,394

1 Claim. (Cl. 62—89.6)

1

The invention pertains to top opening refrigerators and more particularly to an improved arrangement of the insulation and the cooling member for such refrigerators.

It is an object of this invention to provide an improved arrangement of insulation and cooling member for more effectively cooling and circulating the cold air in the storage compartment of a top opening refrigerator.

It is also an object of this invention to provide the insulation and cooling member as a unit which may be conveniently installed into or removed from refrigerator cabinets of the top opening type.

My invention will be more readily understood, and additional objects and advantages thereof will become apparent, by reading the following specification in conjunction with the appended drawing, in which:

Fig. 1 is a front elevational view, partially broken away, for showing the internal arrangement of a refrigerator insulation and cooling unit, in accordance with my invention; and

Fig. 2 is a cross-sectional view thereof, on line 2—2 in Fig. 1, for showing the internal arrangement.

Referring more specifically to the figures of the drawing, I have illustratively disclosed an embodiment of my invention comprising double walls of sheet metal 11 enclosing insulation space 13 which is filled with any suitable insulation 15, which may be glass wool, rock wool, or any other suitable thermal insulating material. The sheet metal walls 11 are of any suitably heavy gauge metal for ample structural strength and rigidity. In such structures, galvanized sheet iron has proven satisfactory and is merely mentioned as one example of a suitable material. Such metal sheets are fabricated to form a hollow or double wall construction in accordance with common practice in sheet metal working and the joints are preferably hermetically sealed, as by soldering for example, to exclude moisture from collecting in the insulation cavity.

As shown, this hollow or double wall insulating structure comprises end walls 17, a bottom wall or floor 19, a front wall 21 and a back wall 23 for enclosing a storage space 25 which opens at the top. The rear wall 23 is extended upwardly, substantially above the other walls, and a top hood wall 27 extends forwardly from the uppermost edge of this back wall. A front hood wall 29 extends from this top hood wall 27 in spaced relation in front of the upwardly extended back wall, and down so that its lower edge is about

even with the upper edges of the front and end walls. The space between the front hood wall 29 and the rear wall is made large enough to receive a cooling member 31 with ample air circulating spaces. Hood end walls 32 are also provided for enclosing the hood space at the ends. The cooling member 31 may be a reversely bent refrigerant tube 33 provided with heat absorbing fins 35 in a conventional construction for conducting any refrigerant vaporizable or otherwise. This cooling member is made of a suitable size so that it extends up the back wall, both in the storage compartment and in the hood enclosed space, and it is mounted on brackets 37 projecting in from the back wall, and arising from the floor.

The insulation and cooling member unit above described, could be utilized, but is preferably first installed by slipping it into the open rear of any suitable conventional top opening refrigerator cabinet 41, to provide a pleasing and finished appearance, as represented by dotted lines. The refrigerant conduit 33 may be extended for connection with any suitable source of refrigerant, which may be remote or, local and mounted in the bottom of the refrigerator cabinet.

By selection of a suitable refrigerant medium or by adjusting the refrigerant supply system (not shown), in a well known manner, a suitable cold storage temperature may be selected and 30 automatically maintained. In operation, extra cold air collects in the hood from whence it descends into the storage compartment 25 producing circulation and more uniformly maintaining the desired low temperature conditions and 35 preserving the stored goods in better condition. In this arrangement it is possible also to get more "low side" or cooling coil into the cabinet which results in maintaining a higher humidity and less shrinkage of meat, vegetables and dairy 40 products.

What is claimed as the invention is:

Refrigeration apparatus comprising a front wall, a bottom wall, two end walls, a back wall, said walls being of a hollow thermal insulating 45 construction and disposed enclosing an open top storage compartment of substantially rectangular cross-section, said back wall extending up substantially above the open top of said compartment, a finned tube cooling member disposed adjacent said back wall both in the storage compartment and thereabove, a thermal insulating hood enclosing a space around the cooling member on the front side of the upwardly extended portion of said back wall, said hood opening downwardly into said storage compartment,

2

and said hood having a front wall disposed vertical and parallel to the back wall which is co-extensive with the back wall of said storage compartment.

NICHOLAS ACHS.
